UNITED STATES PATENT OFFICE.

LOUISE MARIE TAYLOR, OF CHICAGO, ILLINOIS.

MARCEL WAVER.

1,334,329.

Specification of Letters Patent. Patented Mar. 23, 1920.

Application filed September 15, 1919. Serial No. 323,817.

To all whom it may concern:

Be it known that I, LOUISE MARIE TAYLOR, a citizen of the United States, and a resident of Chicago, Cook county, and State of Illinois, have invented certain new and useful Improvements in Marcel Wavers, of which the following is declared to be a full, clear, and exact description.

This invention relates to Marcel wavers for the hair, and its principal object is to provide simple and efficient means for imparting wave like effects to the hair. The invention consists in a plurality of substantially similar, hair waving devices which may be readily secured together so as to temporarily hold and set the hair in the wave like condition which is imparted to it by the waver. The invention further consists in the several novel features of construction, arrangement and combination of parts, hereinafter fully set forth and claimed.

The invention is clearly illustrated in the drawing accompanying this specification, in which:—

Figure 1 is a plan of a Marcel waver for the hair showing a simple embodiment of the invention.

Fig. 2 is a cross section taken on the line 2—2 of Fig. 1.

Fig. 3 is a side elevation of the outer member of one of the hair waving devices, and

Fig. 4 is an end view of one of the hair waving devices.

Referring to said drawing, the reference characters A, B, C, designate several Marcel waving devices for the hair, embodying a simple form of the present invention. The 40 separate hair waving devices are constructed substantially in one and the same manner and one of the devices will be described in detail.

Each hair waving device consists of a 45 perforated, substantially, semi-circular thin, sheet metal outer member 5, preferably formed of aluminum or other thin metal or material, and an inner perforated substantially semi-circular member 6, removably secured to the outer member by spring clips 7, welded, soldered or otherwise secured to one face of the inner member 6. The spring clips project over and down from the edges of the inner member 6, as is seen at 8 in

Fig. 4, and have hook like ends 9, which engage with lugs or other projections, 10, that are provided upon the outer face of the outer member 5. Obviously, any equivalent form of clip or attaching means may be substituted for the one shown, for accomplishing the same result, namely that of temporarily securing together the two members of the hair waving device. Preferably, said spring clips are secured upon the inner members near their outer ends as shown. 65

For the purpose of connecting the several hair waving devices, each is provided on one side, with pins or lugs 11 that project from one side of the outer members 5, and are provided with heads 12 upon their outer 70 ends. The opposite sides of the members 5 are formed with lengthwise extending slots 13, at places opposite to the pins and said slots are formed with enlarged ends 14 through which the headed pins may be 75 inserted. If desired tongues 15 may be left in the enlarged portions 14 of the slots 13, which tongues spring back after the headed pins have been thrust through the enlarged portions of the slots, but which prevent an 80 accidental disconnection of the hair waving devices from each other.

In use, the hair waving devices may be disconnected from each other, and the two members of each waver are then separated. 85 An outer member 5, is then placed below the hair, where the wave like condition is to be produced, and the upper member 6, is then placed over the hair above the outer member and pressed down into the outer member 90 until the spring clips snap over the lugs. The hair is thus bent or curved to conform to the shape of the waver and held in that condition after which a second outer member is placed under the hair adjacent to the 95 first one, the inner member placed over the hair and fastened in place on the outer member, after which the pins 11 are thrust through the enlarged ends of the slots 13 and the two wavers shifted lengthwise of 100 each other to bring pins into the other ends of the slots. This has the effect of bending the hair laterally with respect to the curved lines, imparted to it by the curved shape of the wavers, thus producing not only waves 105 running in parallel lines, but also in transverse lines, giving a zig-zag wave like effect to the hair. Each alternate waver is,

of course, moved in one direction and the intermediate ones moved in the opposite direction to produce this effect.

To facilitate the operation of the waver, 5 the hair is preferably dampened before the hair waving devices are applied thereto, and by providing perforations in the hair waving devices the hair is permitted to dry thoroughly and quickly. It will be understood, 10 by those skilled in this art, that the hair waving devices may be applied to the hair, wherever it is desired to give the wave like effect, and that as many of the wavers may be employed at the time as is found desirable. 15

This device is not to be confused with the ordinary devices for curling the hair, as an entirely different wave line is imparted to the hair with use of a waver, embodying the 20 present invention.

More or less variation of the exact details of construction is possible without departing from the spirit of this invention; I desire, therefore, not to limit myself to the 25 exact form of the construction shown and described, but intend, in the following claims, to point out all of the invention disclosed herein.

I claim as new, and desire to secure by 30 Letters Patent:

1. A Marcel waver for the hair, comprising a plurality of detachably and slidably connected substantially similar hair waving devices each of which consists of an outer 35 and an inner member substantially semi-cir-

cular in cross section, and means for detachably clamping the members of each hair waving device upon the hair.

2. A Marcel waver for the hair, comprising a plurality of substantially similar, hair 40 waving devices detachably connected together and lengthwise movable with respect to each other, each hair waving device consisting of an outer and an inner member, substantially semi-circular in cross-section, 45 and spring clips for securing together members of each hair waving device.

3. A Marcel waver for the hair, comprising a plurality of substantially similar hair 50 waving devices detachably connected with each other, and lengthwise movable with respect to each other, each hair waving device consisting of outer and inner, perforated, semi-circular, nestable members and means for detachably securing together the 55 members of each hair waving device.

4. A Marcel waver for the hair, comprising a plurality of detachably and slidably connected substantially similar hair waving devices, each consisting of outer and inner 60 perforated, substantially semi-circular members, and spring clips for detachably securing the said two members together.

5. A Marcel waver for the hair, comprising a plurality of slidably connected substantially similar hair waving devices, each comprising two hair waving members and means for detachably connecting said hair 65 waving members together upon the hair.

LOUISE MARIE TAYLOR.
